CLAIM

(21) Appl. No.: **29/207,035**

The ornamental design for a cryotherapeutic hemorrhoid pain relief device, as shown and described.

(22) Filed: **Jun. 9, 2004**

DESCRIPTION

(51) **LOC (8) Cl.** **24-02**

FIG. 1 rear view of the present invention;

(52) **U.S. Cl.** **D24/141; D24/133; D24/135; D24/206**

FIG. 2 is a left side view of the present invention;

(58) **Field of Classification Search** D24/141, D24/135, 133, 206, 207; 607/113, 114, 105, 607/108, 112; 606/21, 20, 197; 600/29

FIG. 3 is a front view of the present invention;

See application file for complete search history.

FIG. 4 is a bottom view of the present invention;

(56) **References Cited**

FIG. 5 is a top view of the present invention;

U.S. PATENT DOCUMENTS

FIG. 6 is a right side view of the present invention; and,

4,240,436 A * 12/1980 Singleton 607/108

FIG. 7 is a perspective view of the present invention.
